UNITED STATES PATENT OFFICE.

ROY TAYLOR, OF LOS ANGELES, CALIFORNIA, ASSIGNOR OF ONE-HALF TO DAVID A. CANT, OF LOS ANGELES, CALIFORNIA.

CASING-HEAD APPARATUS.

Application filed April 1, 1925. Serial No. 19,848.

This invention relates to casing-head apparatus. In drilling oil wells it is customary to case or line the hole with several different sizes of pipe or casing, starting at the top with a relatively large size and employing smaller sizes in a telescopic manner until reaching the proper depth, each size being cemented off at its lower end. As each size of pipe must reach to the top of the well it will readily be seen that some method of hanging or landing the pipe must be employed. During the process of drilling, gas under high pressure is frequently encountered. The flow of this gas up through one or more of the well casings often causes serious damage to, and sometimes the total loss of the well. Under the present system it is customary to provide each individual casing with both a landing device and a packing device.

The object of this invention is to provide a simple combination landing and packing device, and one casing head of such construction that it may be used in connection with any of the landing devices to effectively seal the well at any time whether in process of drilling or while cementing the bottom at any size casing, or after the well has been brought in and is producing.

In the embodiment of the invention disclosed in the following specification, the apparatus includes a bottom collar and intermediate collars between the bottom collar and the casing-head, and one of the objects of the invention is to provide simple means for effectively securing these parts together; also to provide apparatus of this kind which is especially adapted for supporting and packing the flow-pipe of a well when it has been brought in.

Further objects of the invention will appear hereinafter.

The invention consists in the novel parts and combination of parts to be described hereinafter, all of which contribute to produce an efficient casing-head apparatus.

A preferred embodiment of the invention is described in the following specification, while the broad scope of the invention is pointed out in the appended claims.

In the drawings:

Fig. 1 is a vertical central section through a casing-head apparatus embodying my invention, showing a number of portions of

the casings; this view illustrates the use of 55 the intermediate collars and also illustrates the means for packing a rod, drill stem, or pipe passing up through the casing-head.

Fig. 2 is a side elevation of the apparatus after the well has been brought in, the 60 strings of casing being broken away.

Fig. 3 is a horizontal section taken through the cap of the casing-head about on the line 3—3 of Fig. 1, and further illustrating the packing means. 65

Fig. 4 is a horizontal section through the casing-head and particularly illustrating the means provided for securing the casing-head and intermediate collars to the bottom collar. 70

Fig. 5 is a vertical section taken about on the line 5—5 of Fig. 4, but upon an enlarged scale, and further illustrating details of the bolt connections for securing the intermediate collars and the casing-head to 75 the bottom collar.

Fig. 6 is a plan of the packing plug and particularly illustrating a modified embodiment of this feature of the invention to adapt the packing plug to pack a rod, such 80 as a Kelly bar, which is of square cross section.

In practicing the invention, I provide a bottom collar 1 which is constructed to rest upon timbers 2 set in the ground at the 85 mouth of the well. This collar is provided with means such as screw-threads 3 for attaching it to the outer casing 4 which is of the diameter which it is usual to put down first in drilling a well.

In order to adapt the bottom collar for use in case an extra large casing is put down, larger than the casing 4, I provide a conical face 5 on the under side of the collar. 90

I provide a casing-head 6. As soon as it becomes necessary to cement off the outer casing 4, this head would be secured to the bottom collar 1. In order to accomplish this, the bottom collar 1 is provided on its upper side with a seat 7 which is preferably of substantially conical form, and on its under side the casing-head 6 is provided with a conical face 8 to be received on the seat 7. Between these faces 7 and 8 a packing ring 9 may be provided for packing the joint between the casing and the bottom collar. The drawing does not illustrate the 100 105 110

2
casing-head seated directly on the bottom collar 1, but shows in Fig. 1 a plurality of intermediate collars 10 which are employed in succession, each collar having a slightly 5 smaller threaded opening 11 than the one below it so as to adapt these collars for attachment to inner casings of successively smaller diameters. The packing rings 9 may be countersunk into circumferential 10 grooves 12 formed in the seat 7 of the bottom collar and in the seats 13 of the intermediate collars.

I provide means for securing the casing-head to the bottom collar either directly or 15 indirectly when one or more of the intermediate collars have been placed in position between the bottom collar and the casing-head. In order to accomplish this, I provide the bottom collar with a flange 14 and 20 this flange is provided with slots or openings 15. These slots or openings receive a plurality of parallel connecting bolts preferably built up of bolt sections or bolts 16 which extend upwardly (see Figs. 2 and 5) 25 and have threaded upper ends which extend through slots 17 in lugs 18 of the adjacent collar. The threaded upper end of each connecting bolt 16 carries a nut 19 which screws down onto the upper face of the lug 30 18. Furthermore, the threaded end of the connecting bolt 16 extends above this nut and receives a threaded socket 20 formed on the lower end of an upper connecting bolt 21. The upper end of this bolt 21 is constructed like the upper end of the bolt 16 and receives a nut 22 which screws down onto the lug 18 of the next adjacent collar. In this way all of the intermediate collars are clamped to the bottom collar. The uppermost intermediate collar is secured in 40 this same way to a flange 23 (see Fig. 2) which is carried at the lower end of the casing head 6.

In this way, the collars are all connected 45 together in a column and the spaces between or around the inner casings are packed off from each other. The result of this is that a number of annular gas chambers or gas rings 24 are formed (see Fig. 1). By reason of the fact that the bolts 16 are 50 parallel with each other, they can connect any number of collars in place without changing their position. Hence the clamping nuts will always seat flat on their lugs. The collars are all provided with individual 55 outlet connections 25 through which the gas may be led off to gas collectors.

The casing head 6 is provided with outlet 60 connections such as connection 26 for carrying off oil, mud, or gas, and above these outlet connections the packing chamber 27 is formed in the casing head. This packing chamber is formed above a transverse wall or partition 28 which is preferably in the 65 form of a removable segmental disc which

is received upon a tapered seat 29 formed within the casing head. This transverse wall therefore operates as a bottom for the packing chamber 27. In the packing chamber I provide packing means for packing a round rod or a pipe 30 passing through the casing head. I also provide means for compressing the packing and exerting a thrust on its compressible body radially inward toward the vertical axis of the head. 75

In practice I prefer to provide a packing plug which includes the bottom plate 28 as a part of it, and above this plate the body 31 of the plug is received. This body is of compressible material such as soft rubber, 80 and is preferably constructed so that its middle portion can be readily moved inwardly. In order to make this operation effective, I prefer to construct the body 31 with a plurality of radial slots 32 which 85 extend outwardly from a central opening 33 formed through the packing (see Fig. 3), but these slots terminate short of the periphery 34 of the plug body. I provide means movably mounted on the casing-head 90 and capable of being drawn down on the casing-head for compressing the packing body 31 against the rod or pipe 30. For this purpose, I provide a cap 35 in the form of a ring with means such as screw-threads 36 connected with the casing-head so that when the cap is rotated it will move down on the head. Any suitable cooperating construction may be provided to enable the cap to compress the packing when screwed down in this way. 95

I prefer, however, to provide the packing plug with a flexible ring 37 of metal which lies in an annular recess 38 formed on the upper side of the packing body. This ring extends around the central vertical axis of the casing-head and is preferably anchored to the bottom plate 28 by anchor bolts 39 which extend downwardly through the 100 plate. 110

On this ring are pivotally mounted a plurality of dogs 40. The cap 35 is preferably provided with a large opening 41. This opening is of sufficiently large diameter to enable the entire packing plug to be passed down through it. This would be done before the cap 35 is screwed down as far as the position in which it is indicated in Fig. 1, and when the plug has been shoved down into position in this way, the upper ends of the dogs 40 which are tapered as indicated at 42 engage the inner side of the cap. In this way, the dogs 40 will assume an inclined radial position. When the cap is screwed down, therefore, these dogs will exert an inward thrust against the middle portion of the compressible body 31 of the packing and press the same forcibly against the side of the rod or pipe 30 to be packed. The ring 37 should be made of stout wire 115 120 125 130

or a bar, but is preferably in the form of a split ring so that it will be readily flexible or collapsible inwardly under the action of the force exerted by the dogs.

5 I prefer to construct the packing plug so that it will permit the tool string to be pulled up through it after it has been put in place; in other words I construct it so that it will permit the joints or couplings such 10 as the coupling 43 to pass upwardly. In order to accomplish this, I provide an opening 44 through the bottom plate 28 which is of sufficiently large diameter to permit a joint or coupling 43 to pass through the 15 plate. This of course means that this opening 44 is of considerably larger diameter than the opening 33 already referred to which is formed at the center of the packing body 31.

20 It might happen that gas would be struck in drilling a well while a square bar such as a Kelly bar is located at the head. In order to adapt the apparatus for such a contingency, I provide a compressible packing body 45 of special form (see Fig. 6) in which the central opening 46 is of square form to suit the dimensions of the Kelly bar. In other respects the construction of this 25 packing body 45 is substantially the same 30 as that described above for the packing body 31. In other words, I provide a split metal "ring" 47 which is flexible but which is substantially square in form. In this case there would be four dogs 48 each dog being 35 pivoted on one of the sides of the split ring. Furthermore, the opening 49 through the bottom plate would be of square form as indicated by the dotted line in Fig. 6.

I provide means operating, after the well 40 has been brought in, to support and anchor a flow-pipe such as the flow-pipe 50 (see Fig. 2). For this purpose I provide long tie-bolts 51, the lower ends of which are anchored in the flange 14 which projects 45 outwardly from the lower portion of the bottom collar 1. This flange 14 is supported on suitable timbers 22 and the head 53 of each tie-bolt may be recessed in the upper 50 face of the timber (see Fig. 1). At their upper ends these tie-bolts 51 are attached to a clamp 54 which is attached as a cross-head to the flow-pipe 50 above the valves 55 and T connection 56.

55 It is evident that the casing-head will operate as a blow-out preventer by reason of the fact that the compressible body 31 of the packing will not permit the escape of gas under a dangerous pressure, thereby allowing the gas to be diverted into the pressure vents, flow lines, etc., and preventing the casing head from being blown off.

It is understood that the embodiment of the invention described herein is only one of the many embodiments this invention may take, and I do not wish to be limited

in the practice of the invention, nor in the claims, to the particular embodiment set forth.

What I claim is:—

1. In a casing-head apparatus, the combination of a bottom collar having means for securing the same to an outer casing, and having a seat on its upper side, an intermediate collar received on said seat and threaded for securing the same to an inner 70 casing, said intermediate collar having a seat on its upper side, a casing-head received on said last named seat, and means for securing the intermediate collar and the casing-head to the bottom collar. 75

2. In a casing-head apparatus, the combination of a bottom collar with means for securing the same to an outer casing, and having a seat on its upper side, a casing-head above the seat, means for securing the 80 casing-head to the bottom collar, said casing-head having an outlet connection with a packing chamber above the outlet connection, a compressible packing plug received in the packing chamber, a cap for the casing-head with means for drawing the same down onto the casing-head, and a plurality of members engaged by the cap for forcing the packing plug inwardly and toward the 85 vertical axis of the casing-head. 90

3. In a casing-head apparatus, the combination of a bottom collar with means for securing the same to an outer casing and having a seat on its upper side, a casing-head above the seat, means for securing the casing-head to the bottom collar, said casing-head having an outlet connection with a packing chamber above the outlet connection, a compressible packing plug received in the packing chamber having a body of 100 compressible material with a flexible anchor ring extending around the vertical axis of the casing-head, a cap for the casing-head with means for drawing the same down onto the casing-head, and dogs carried by the 105 flexible ring for engaging the cap and co-operating with the cap to produce a radial inward thrust upon the inner portion of the body of the plug. 110

4. In a casing-head apparatus, the combination of a bottom collar with means for securing the same to an outer casing, and having a seat on its upper side, a casing-head above the seat, means for securing the casing-head to the bottom collar, said casing-head having an outlet connection and having a packing chamber above the outlet connection, a packing plug received in the packing chamber, having a body of compressible material and having a flexible metal ring 120 surrounding the vertical axis of the casing-head, a cap in the form of a ring with a central opening to permit the plug to be passed down through the cap, and having a 125 thread connection with the casing-head to en- 130

able the cap to be screwed down onto the casing-head, and a plurality of dogs pivotally mounted on the metal ring constructed to engage the cap and assume an inclined position, and cooperating with the cap when screwed down to exert a radial inward thrust on the compressible body of the plug.

5. In a casing-head apparatus, the combination of a bottom collar with means for 10 securing the same to an outer casing, and having a seat on its upper side, a casing-head above the seat, means for securing the casing-head to the bottom collar, said casing-head having an outlet connection and a packing chamber, and having a transverse wall above the said outlet connection forming the bottom of the packing chamber, said transverse wall having an opening therethrough to pass a rod or pipe, a compressible 15 packing plug seating on the transverse wall having a body of compressible material, a cap having a thread connection with the casing head, permitting the cap to be screwed down on the head, and radially disposed members cooperating with the cap to clamp 20 the body of the packing plug against the rod or pipe passing through the casing head.

6. In a casing-head apparatus, the combination of a bottom collar with means for 30 securing the same to an outer casing, and having a seat on its upper side, a casing-head above the seat, means for securing the casing-head to the bottom collar, said casing head having an outlet connection and a 35 packing chamber above the outlet connection, a compressible packing plug received in the packing chamber having a body of compressible material with a central opening to receive a rod or pipe passing through the casing-head, the body of said plug having substantially radial slits extending from the central opening outwardly and terminating short of the edge of the compressible body, said packing plug having a flexible metal ring 40 extending around the vertical axis of the casing head, a cap having a thread connection with the head enabling the cap to be screwed down onto the head, and a plurality of dogs carried by the said metal ring 45 constructed to engage the cap and cooperate with the same to exert an inward radial thrust upon the compressible body of the packing plug to pack the rod or pipe passing through the casing head.

55 7. In a casing-head apparatus, the combination of a bottom collar with means for securing the same to an outer casing, and having a seat on its upper side, a casing-head above the seat, means for securing the casing-head to the bottom collar, said casing-head having an outlet connection and a packing chamber above the outlet connection, said casing head also having an inner seat 60 between the gas outlet connection and the packing chamber, a plate at said inner seat,

a packing plug having a body of compressible material with a split ring extending around the vertical axis of the casing head, means for anchoring the split ring to the said plate, a cap for the casing-head with 70 means for drawing the same down onto the casing head, and a plurality of dogs pivotally mounted on the split ring constructed to engage the cap when the same is drawn down onto the casing-head and cooperating 75 with the cap to exert an inward radial thrust in the compressible body of the plug.

8. In a casing head apparatus, the combination of a bottom collar having means for attaching the same to an outer casing and having a seat on its upper side, an intermediate collar received on said seat, said intermediate collar having a seat on its upper side, a casing head received on said last named seat, said casing head and said collars having flanges with aligning slots, parallel connecting bolts received in the slots and cooperating with the flanges to secure the intermediate collar and the casing head to the bottom collar, packing rings between the 80 intermediate collar and the casing head and between the intermediate collar and the bottom collar, and packing means carried by the casing head.

9. In a casing head apparatus, the combination of a bottom collar having means for attaching the same to an outer casing and having a seat on its upper side, an intermediate collar received on said seat and having a seat on its upper side, a casing head received on the last named seat, said intermediate collar and said casing head having flanges with aligning slots on the sides thereof, a connecting bolt secured in the bottom collar and having a threaded upper end extending past the flange of the intermediate collar, a nut carried on the said threaded upper end of the bolt and engaging the flange of the intermediate collar to clamp the intermediate collar on the bottom collar, an extension bolt having a threaded socket received on said threaded upper end of the bolt above said nut and having a threaded upper end extending above the flange of the casing head, and a nut on the extension bolt engaging the flange of the casing head for securing the casing head to the intermediate collar.

10. In a casing head apparatus, the combination of a bottom collar having means for attaching the same to an outer casing and having a seat on its upper side, an intermediate collar received on said seat and having a seat on its upper side, a casing head received on the last named seat, said intermediate collar and said casing head having lugs with aligning slots on the sides thereof, a connecting bolt secured in the bottom collar and having a threaded upper end extending past the lug of the intermediate col-

- lar, a nut carried on the said threaded upper end of the bolt and engaging the lug of the intermediate collar to clamp the intermediate collar on the bottom collar, an extension bolt having a threaded socket received on said threaded upper end of the bolt above the said nut and having a threaded upper end extending above the lugs of the casing head, and a nut on the extension bolt engaging the flange of the casing head for securing the casing head to the intermediate collar, a flow pipe extending up through the casing head means in the casing head for packing the flow pipe, a cross-head attached to the flow pipe above the casing head, and tie-bolts anchored at their lower ends in the bottom collar and secured to the said cross head.
11. In a casing head apparatus, the combination of a casing head having a packing chamber with a transverse wall constituting the bottom of the packing chamber, said transverse wall having an opening therethrough, a packing plug having a body of compressible material received in the packing chamber and resting on said transverse wall, said plug having an opening therethrough of smaller diameter than the first named opening, and means for exerting pressure on the body of the plug to force the inner portion of the same radially inward. 30
12. In a casing head apparatus, the combination of a casing head having a packing chamber with a transverse wall constituting the bottom of the packing chamber, said transverse wall having an opening therethrough, a packing plug having a body of compressible material received in the packing chamber and resting on said transverse wall, said plug having an opening therethrough of smaller diameter than the first named opening, a cap mounted on the casing head in the form of a ring with an opening therethrough sufficiently large to permit the said plug to pass down through the same, 40 means connecting the cap with the casing head to force the cap down toward the packing, and a plurality of members carried by the plug cooperating with the cap to exert pressure on the packing plug in a radial direction to force the inner portion of the same radially inward. 45
13. In a casing head apparatus, the combination of a casing head having a packing chamber with a transverse wall constituting the bottom of the packing chamber, said transverse wall having an opening therethrough, a packing plug having a body of compressible material received in the packing chamber and resting on said transverse wall, said plug having an opening therethrough of smaller diameter than the first named opening, a cap mounted on the casing head in the form of a ring with an opening therethrough sufficiently large to permit the said plug to pass down through the same, 50 means connecting the cap with the casing head to force the cap down toward the packing, and a plurality of members carried by the plug cooperating with the cap to exert pressure on the packing plug in a radial direction to force the inner portion of the same radially inward. 55

Signed at Los Angeles, California, this 20th day of March 1925.

ROY TAYLOR.
